HYDRAULIC CHECK

Courtney N. Mitchell, Strongsville, Ohio

Application July 15, 1935, Serial No. 31,386

34 Claims.

(Cl. 16—52)

This invention relates, as indicated to hydraulic checks and is directed to a check which may be used for numerous purposes where the relative movement of two associated parts must be controlled. It is particularly suited to the control of doors and provides the force necessary to bring the door into its closed position as well as controlling the movement of the door during its closing and opening and thus prevent damage being done by the door moving too rapidly.

Heretofore, checks of this general type have lacked the necessary features for universal application due to the absence of convenient means of reversing the action of the devices, due to the lack of means for regulating the forces exerted by the operating spring, due to lack of control for variations caused by changes in temperature and due to no convenient means for adjusting the resistances at various operating positions.

The principal object of this invention is to provide a hydraulic check which is not only reversible as to direction of rotation, but one which has means for gradually varying the tension in the operating spring. Another object is to provide a check with convenient adjustments for a variety of operating conditions. Another object is to provide a compact and convenient means of temperature control. A further object is to provide a means of preventing leaks. A still further object is to provide a means whereby the operating spring may be secured against localized strains which result in breakage. Another object is to provide an ample reservoir of working fluid. An additional object is to provide a system of valves which operate with negligible resistance. Another object is to provide a unit which can be made from inexpensive parts and which can be assembled at low cost. To the accomplishment of the foregoing and related ends, said invention, then, consists of the means illustrated in the accompanying drawing, described in the following specification and more particularly pointed out in the appended claims.

The annexed drawing and the following description set forth in detail certain mechanism embodying the invention, such disclosed means constituting, however, but one of various mechanical forms in which the principle of the invention may be used.

In the said annexed drawing Fig. 1 is a vertical section taken on line 1—1 of Fig. 2. Fig. 2 is a section on line 2—2 of Fig. 1. Fig. 3 is a section substantially on line 3—3 of Fig. 2 showing the spring barrel 19 partly in section and partly in elevation. Fig. 4 is a section on line 4—4 of

Fig. 3 showing the central parts only. Fig. 5 is a section substantially on line 5—5 of Fig. 1. Fig. 6 is a section on line 6—6 of Fig. 1. Fig. 7 is a partial section on line 7—7 of Fig. 1 showing the piston and valve structure only. Fig. 8 is a partial section on line 8—8 of Fig. 1 and constitutes a plan view of the piston only.

In the embodiment illustrated, the housing 10 is provided with a bracket 11 welded thereto and serving as a means of attaching the check to 10 the door or other object with which it is used. The top of the housing is provided with a cover 12 which has an annular groove 13 serving as a reservoir. The housing has an outwardly extending flange 14 which engages the inwardly extending flange 15 of the flange ring 16. The flange ring 16 is provided with internal threads engaging threads on cover 12 for the purpose of holding this cover in assembled relation with the housing. The upper face of flange 14 is recessed as at 17 to provide space for an elastic gasket. Adjacent the recess is the edge 18 provided to limit the position of the cover 12 and which is machined to provide a definite depth for the housing.

Rotating within the housing is spring barrel 19. A recess machined in cover 12 serves as the upper bearing for this spring barrel and the port ring 20 is constructed to provide the lower bearing. The spring barrel is provided with an extension 21 of reduced diameter which serves as a shaft for the attachment of operating lever 22. This extension has a conical portion provided with hardened flutes 23 which engage the bore of lever 22. This lever is held in place by screw 24. This screw is provided with an axial bore into which is inserted the rivet 25 held in place by spring 26. This rivet, which may have a seat of soft material, serves as a vent valve to relieve the pressure which may develop within the check and which would otherwise cause leaks around the shaft packing, 27. This packing surrounds the shaft extension 21 and engages a beveled recess provided in cover 12. It is retained by cup 28 which is held in position by spring member 29. This spring is formed at 30 to engage a recess in lever 22 and in the position shown exerts pressure on cup 28.

In the annular space surrounding spring barrel 19 are abutment 31 and wing piston 32 each of which extends between cover 12 and port ring 20. The abutment is provided with a longitudinal groove 33 engaging projections or keys 34 and 35 stamped in the wall of the housing 10. The key 34 extends partly into a slot provided in cover 12.

12 to hold the cover in correct angular position and key 35 engages a slot in port ring 20, likewise to maintain correct angular relation of parts. The abutment 31 is provided with an upper passage 36 intersecting transverse port 37 and connected by passage 38 with the reservoir 13. Likewise there is a lower passage 39 intersecting transverse port 40 and connected with the annular space 41 under port ring 20 by a passage 10 through the port ring. A pair of leaf springs 42 and 43 secured to the abutment by rivet 44 serve as valves for the passage of liquid from reservoir 13 and annular space 41 to the working compartments, but automatically seal the connecting passages against a reverse flow.

The piston 32 is provided with inwardly extending keys 45 engaging slots in the wall of spring barrel 19, this engagement serving as a positive means of rotating the piston when the spring barrel rotates. These keys fit loosely in the slots of the spring barrel and thus permit the piston to oscillate under the hydraulic pressures and form a seal with the wall of the housing 10 when variations occur in this wall or in the spring barrel. The slots in the spring barrel are somewhat longer than the keys 45 to permit the piston to be centralized in the space between cover 12 and port ring 20 regardless of minor variations in the axial position of the spring barrel. The central outer part of the piston is flattened as at 46 to limit the contact with the wall of the housing to the outer edges and thus prevent a tendency to cause a wedging action between the piston and the housing.

35 Within the piston 32 is valve 47 controlling the flow through ports 48. This valve has a reduced stem 49 surrounded by the coiled thermostatic element 50 which has its one end engaging valve 47 and its other end anchored in adjustable plug 51. This plug is provided with fine axial, flutes engaging corresponding flutes in the end of the piston 32 and which permit of angular adjustment for the initial setting of the thermostatic valve.

45 The lower face of cover 12 is provided with an annular groove containing the severed ring member 52. This ring member is held in the groove by pins as indicated at 53 and is rotated by means of the small spur gear 54 attached to shaft 55 and engaging fine gear teeth die cast in ring 52. This ring is made in the form of an inverted channel through a part of its circumference, these channel shaped spaces serving as adjustable relief passages between the working compartments.

55 The relief is provided by the piston 32 passing over the edges of the ends of the channel sections as at 56 in Fig. 5 thus permitting a quick movement of the piston by the relief of the hydraulic pressure. The groove containing ring 52 is discontinuous at the abutment as shown at 57 and the ring is provided with an opening somewhat wider than this to permit of limited angular movement for the adjustment above referred to.

65 Adjacent the abutment at both sides are ports 58 and 59 connected by passage 60. This latter passage is controlled by valve 61 having packing 62 and gland 63 to prevent leakage, the valve 61 being a primary means of adjustment. The arm 64 serves as a means of adjusting this valve and thus regulates the flow of liquid from one working compartment to the other through the entire range of travel of the piston. Supplementing the primary control as provided by valve 61 is valve 65 engaging the passage 66 provided in port ring 20 and comprising a secondary means

of regulation. This passage 66 is formed by inserting a thin walled tube of suitable diameter and form in the die when the port ring is cast. As a further means of regulation, the ports 67 and 68 extending through the port ring into annular space 41 are provided and form a limited range of free movement for the piston.

It will be evident that, as the piston 32 is moved in a clockwise direction by spring actuated barrel 19, reference being had to Fig. 2, the liquid contained in the portion 69 of the annular space around the spring barrel will have three passages for escape. During the first few degrees of movement most of the flow will take place through port 68, annular space 41 and then through port 67 into space 70. Some of this liquid will move through passage 39 and port 40 into compartment 70. The ports 67 and 68 being relatively large there will be a very little hydraulic resistance during this limited movement. A continuation of the movement of the piston 32 closes port 68 and causes flow to occur through passage 66 past valve 65. This flow continues until the piston has moved about 90° at which time the entrance to passage 66 is covered by the piston. As the piston moves farther, the only source of escape of liquid is through ports 58, 59 and 60 and past valve 61. The speed of the door or other object to which this instrument is attached, will thus be reduced by steps, the speed being dependent on the size of the ports and the adjustments of the valves. As the piston continues to move farther under the adjustment provided by valve 61, it will approach abutment 31, but before reaching a position adjacent this abutment and which is the position it occupies when the door is fully closed, the piston will pass the edge 56 of ring 52, Fig. 5, and suddenly release the pressure in space 69 by permitting flow past the upper end of the piston and through the channel shaped end of ring 52 into space 70 which now has become much larger due to the movement of the piston. The angular position of the piston at the time of this release is determined by the position of ring 52 which is adjusted by means of gear 54 as already explained.

To provide additional flow of liquid from space 69 to space 70 at the time of release the spring barrel 19 is cut away as at 69' and 70' providing a free passage when either of these cut-away sections comes into position opposite the abutment 31, these cut-away sections being somewhat wider than the abutment.

As all ports and passages are symmetrical about line 1—1 of Fig. 2 the instrument will operate in either direction insofar as the hydraulic structure is concerned. However, the direction of rotation of the spring barrel 19 under the action of spring 71 must be reversed. This is accomplished in a manner similar to that shown in my Patent No. 1,836,383. In the device shown on the annexed drawing, the spring 71, which is of helical form, has its upper end secured to anchor 72 and its lower end secured to anchor 73, the cups 72' and 73' serving as means for centering the spring on the anchors. This centering of the spring from the outside of the coils prevents contact with the hub of the anchor which would result in localized bending of the coil at the point of contact and eventual fracture of the coil at that point. These cups, further prevent frictional contact of the spring with the spring barrel which would detract from its free movement, the outer diameter of the cups being somewhat 75

smaller than the inner diameter of the spring barrel.

The anchors are rotatably mounted on shaft 14 which is piloted in the spring barrel extension 21 at its upper end and in a hole through the bottom of the housing 10 at its lower end. Washer 75 having lugs engaging keyways 76 serves as a seat for the nut 77. The bottom of the housing 10 is clamped between washer 75 and anchor washer 78 which bears against the shoulder on shaft 14. The anchor washer has lugs also engaging keyways 76 and is provided with sharp hardened flutes which serve as a means of positive engagement with the soft steel of the housing to prevent rotation of shaft 14. Washer 75 has a notch 75' which serves as a means of engagement for a tool to hold shaft 14 from rotating while tightening nut 77. A gasket 79 is inserted between the washer 75 and the housing 10 to prevent leaks and to furnish additional holding friction.

The upper spring anchor 72 is provided with an external lug 80 which engages lug 81 provided on the inside of the spring barrel, and with an inner lug 82 engaging anchor pin 83 securely driven into shaft 14. The lower spring anchor 73 is centered in tension block 84 and securely held from rotation relative thereto by adjusting screw 85. This tension block has turning clearance in housing 10. The upper and lower external corners of the tension block are cut away at 86 and 87 through the greater part of their circumferences leaving a double lug 88. The lower part of this lug 88 engages lug 89 on the anchor washer 78 and the upper part of the lug engages lug 90 on the spring barrel 19. The relative positions of these various lugs are shown most clearly in Figs. 3 and 4. From these figures it will be evident that when the spring barrel 19 is rotated in a clockwise direction, the lug 81 of the spring barrel engaging lug 80 of the spring anchor 72 will rotate it on shaft 14 causing the inner lug 82 to move away from pin 83. During this movement the spring 71 is wound up from its upper end and the lug 90 moves away from lug 88, the tension block 84 being held from turning by lug 89 on anchor washer 78 which is securely clamped in position by the nut 77 on the end of shaft 14 as above explained.

When the spring barrel 19 rotates in an anti-clockwise direction it will be evident that lug 81 will move away from lug 80 of the spring anchor 72 and lug 82 will engage pin 83 and thus prevent the upper end of the spring and its anchor from rotating relative shaft 14. The lug 90 of the spring barrel now engages the lug 88 of the tension block 84 rotating this block, and the lower spring anchor secured thereto, on shaft 14 thus winding up the spring 71 from its lower end in a direction opposite to the wind-up at the other end.

In order to secure sufficient range of angular movement of the spring barrel, the movement of piston 32 must begin in proximity with one side of the abutment 31 for rotation in one direction and in proximity with the other side of the abutment for rotation in the opposite direction. To attain this condition, nut 77 is loosened and the spring barrel 19, carrying the spring, the spring anchors, shaft and all related parts including the piston, is rotated until the piston 32 contacts with the abutment 31. In this position nut 77 is securely tightened. The spring barrel can then be rotated in one direction winding up spring 71 from one end. If the nut 77 is tightened with the piston

adjacent the other side of the abutment as an initial position, the spring barrel will rotate in the opposite direction winding the spring 71 from its other end.

In order that the tension of spring 71 may be changed to conform with operating conditions, the spring anchor 73 is provided with a worm wheel structure at 91 engaging the adjusting worm or screw 85 which has a bearing at one end in tension block 84 and at the other end in screw plug 92 carried in the tension block. As shown in Fig. 3 the recess in the tension block for the reception of the adjusting worm is located within lug 88. In order to make this adjusting worm accessible when the instrument is adjusted for either clockwise or anti-clockwise rotation, two openings are provided as at 93 and 94, one being for adjustment when the check operates in a clockwise direction and the other when it operates in an anti-clockwise direction. The band 95 is shrunk or welded to the outside of the housing 10 to provide stock for the threads of plugs 96 inserted at 93 and 94. It will be evident that, when a screw driver or suitable wrench is inserted in one of these openings and the adjusting worm turned, the lower spring anchor 73 will be rotated and the tension of the spring 71 will be changed without affecting the position of the tension block 84.

In order to prevent pressures from building up within the instrument at points where leakage might occur through adjacent joints, the reservoir 13 is maintained substantially at atmospheric pressure by passages connecting this reservoir with the space directly below vent valve 25. This valve being held to its seat by a very light spring 26 permits the escape of gases under very light pressures. Transverse passage 97 in association with passage 98 connects the circumferential passage 99 adjacent gasket 17 and circumferential passage 100 with the reservoir. The hole 101 leading into the spring barrel 19 is joined by notch 102, Fig. 4, and groove 103 with the space in shaft extension 21 adjacent valve 25, thus bringing both circumferential passages 99 and 100 as well as the reservoir 13 into communication with a space substantially at atmospheric pressure. Pressures of any appreciable magnitude are thus prevented from developing adjacent gasket 17 or adjacent packing 27. The instrument may be filled by removing the plug in the top of passage 98 or by removing lever screw 24. A hole 104 is provided in the spring barrel 19 connecting the annular space 41 with the interior of the spring barrel. This passage permits of the circulation of the fluids during the filling operation and subsequent thereto.

It will be evident that as piston 32 moves past port 67 during the opening of the door, the flow through this port is interrupted and a sudden increase of pressure at this point will occur, dependent, of course, on the adjustment of valves 61 and 65. This sudden increase in pressure retards the further movement of the door and prevents it from swinging around rapidly and causing damage by collision with other objects.

Attention is directed to the simplicity of the various parts entering into the construction of this device which permits of inexpensive methods of manufacture. The housing 10 is made very inexpensively of sheet metal with no interior machining or grinding required. The cover 12 is of such form as to be machined fully, except for small drilled holes, in one set-up and from a very simple casting. The spring barrel 19 with

its extension 21 is made very economically by providing a top member made on an ordinary screw machine and then welding this top to a piece of tubing of suitable size after which the assembly thus formed is passed through a centerless grinder to insure a correct outer diameter. Other parts such as piston 32, abutment 31, spring anchor 72, port ring 20 and tension block 84 are produced at very low cost as die castings requiring very little if any machining, the construction of the entire unit being such as to permit of considerable variation in the dimensions of practically all parts.

Other modes of applying the principle of my invention may be employed instead of the one explained, change being made as regards the mechanism herein disclosed, provided the means stated by any of the following claims or the equivalent of such stated means be employed.

I therefore point out and distinctly claim as my invention:

1. In a hydraulic check, a casing having an abutment therein, a spring barrel within said casing, a channel surrounding the spring barrel, a vane in the channel being secured to said spring barrel, means for oscillating said spring barrel, a spring for returning said spring barrel to its original position, means arranged within said casing and moveable to different positions to connect said spring barrel with either end of said spring, and means for regulating the tension of said spring.

2. A hydraulic check of the class described comprising a casing having an abutment, a spring barrel within said casing and dividing the same into a pair of compartments and having a portion projecting through said casing, the abutment and a piston being in one of the compartments, a lever non-rotatably secured to said projecting portion, a shaft arranged within said spring barrel, a spring associated with said shaft, spring anchors supported by said shaft and connected to the opposite ends of said spring, manually operable means carried by said shaft and adapted to be selectively positioned to connect said spring barrel with either one of said spring anchors and to hold the other spring anchor against turning whereby said spring may be wound up from either end selectively and a means for adjusting the position of one of said spring anchors relative said shaft.

3. In a hydraulic check, a casing having an abutment and a piston therein forming a pair of working compartments, a spring actuated member serving as a rotatable shaft in said casing, the piston being operated by said spring actuated member, a cover for said casing, said cover including a reservoir, and a leaf spring check valve adapted to deliver liquid from said reservoir to one of said working compartments.

4. In a hydraulic check, a casing having an abutment and a piston therein forming a pair of working compartments, a spring actuated member serving as a rotatable shaft in said casing, the piston being operated by said spring actuated member, a cover for said casing, said cover including a reservoir, a check valve comprising a flexible element covering a passage from said reservoir and a vent valve adapted to relieve pressures within said reservoir.

5. In a hydraulic check, a casing, a hollow cylinder serving as a shaft, a piston in said casing and operable by said cylinder, an abutment, said piston and said abutment in association with the casing and the hollow cylinder defining two work-

ing compartments, a cover for said casing, a primary means of adjustment associated with said cover and adapted to regulate the flow of liquid between said working compartments and a secondary means of adjustment independent of 5 said primary means of adjustment, the flow through the said secondary adjustment dependent upon the position of the aforesaid piston.

6. In a hydraulic check, a casing, a rotatable cylinder serving as a shaft, a piston in said 10 casing and operable from said rotatable cylinder, an abutment, said abutment in association with said shaft and said piston forming a partition between two working compartments, a valve in 15 said partition, said valve having an elongated stem, a part of said valve cut away to provide a variable passage, a coiled thermostatic element surrounding the stem of said valve, and a means for adjusting the initial position of said valve.

7. In a hydraulic check, a casing, a rotatable 20 cylinder serving as a shaft being journaled in said casing, a piston operable from said rotatable cylinder, an abutment, said piston and said abutment in association with the cylinder and casing defining a pair of working compartments, a 25 passage between said working compartments, said passage being controlled by the aforesaid piston, and means for adjusting the position of said passage.

8. In a hydraulic check, a casing, a cover for 30 said casing, a hollow cylinder serving as a shaft being journaled therein, a piston operable from said hollow cylinder, a reservoir, a vent valve adapted to relieve the pressure in said reservoir, an annular vent passage in said cover and a 35 passage connecting said annular vent passage and said reservoir.

9. In a hydraulic check, a casing, a tubular member serving as a shaft being journaled in said casing, a piston in said casing and operable 40 from said tubular member, an orifice in a wall of said casing, said orifice constituting a fixed adjustment for controlling the movement of the piston through a portion of its travel, and a valve adjustable to regulate the movement of the piston 45 through other parts of its travel.

10. In a hydraulic check, a casing, a member serving as a rotatable shaft being journaled in said casing, a piston in said casing and operable by said member, an orifice in the wall of the casing, said orifice constituting a fixed adjustment 50 for controlling the movement of said piston through a portion of its travel, and a second orifice having a manual adjustment, the said second orifice being closed by the movement of said 55 piston.

11. In a hydraulic check, a casing, a rotatable member serving as a shaft being journaled in said casing, a piston in said casing and operable from said rotatable member, a vent passage constituting 60 an adjustment for the initial movement of said piston, a second passage constituting an adjustment for a further movement of said piston and a valve adapted to regulate the movement of the piston beyond the control of the said second 65 passage.

12. In a hydraulic check, a casing, a rotatable member serving as a shaft being journaled therein, a piston in said casing and operable from said shaft, a vent passage constituting an adjustment 70 for the initial movement of the said piston, a second passage constituting an adjustment for a further movement of said piston, a valve adapted to regulate the movement of said piston beyond the control of the said second passage and 75

means for releasing pressure controlled by the said valve upon a continued movement of the said piston.

13. In a hydraulic check, a casing, a rotatable member serving as a shaft being journaled therein, a piston in said casing and operable from said rotatable member, a vent passage constituting an adjustment for the initial movement of the said piston, a second passage constituting an adjustment for a further movement of said piston, a valve adapted to regulate the movement of said piston beyond the control of the said second passage, and an adjustable means for releasing pressure controlled by the said valve.

14. In a hydraulic check, a casing having a pair of working compartments, a rotatable member serving as a shaft being in said casing, a piston operated by said rotatable member, a cover for said casing, a reservoir associated with said casing, a check valve comprising a flexible element covering a passage from said reservoir, said valve controlling the flow of liquid through passages from the reservoir.

15. In a hydraulic check, a casing having a pair of working compartments, a rotatable member serving as a shaft being in said casing, a piston operated by said rotatable member, a spring adapted to return the said shaft to its initial position, anchors for said spring, and means for centering the coils of said spring with respect to said anchors.

16. In a hydraulic check, a casing, a rotatable member serving as a shaft being journaled in said casing, a piston operable by said shaft, a cover for said casing, said rotatable member having an extension projecting through said cover, a lever attached to said extension, packing engaging said cover and said extension, a retainer for said packing and spring means associated with said lever and engaging said retainer whereby said packing is compressed.

17. In a hydraulic check, a casing, a rotatable member serving as a shaft being journaled in said casing, a wing piston operable by said rotatable member, said piston and said rotatable member provided with key means of interconnection, said key means having clearance adapted to permit of limited oscillatory movement of said piston relative to the key means in said rotatable member.

18. In a hydraulic check, a casing, a rotatable member serving as a shaft being journaled in said casing, a piston operable by said rotatable member, an abutment associated with said casing and said rotatable member, said abutment and said casing being provided with interengaging means, said means having clearance and adapted to permit a limited movement of said abutment relative to the casing.

19. In a hydraulic check, a casing, an arm actuated member serving as a shaft within the casing, said casing and said arm actuated member defining an annular channel, a wing piston in said channel, the wing piston being secured to the arm member, means for oscillating said member, a return spring having connection within said member, and adjusting means within the casing for changing the tension of said spring.

20. In a hydraulic check, a casing having an abutment keyed therein, a hollow member serving as a shaft in said casing, an annular channel surrounding said hollow member, a piston being operated by said hollow member, the said piston and said abutment dividing the annular channel into two working chambers, a spring adapted to

return the hollow member to its initial position, anchors for said spring, and screw actuated means for adjusting the relative positions of said anchors.

21. In a hydraulic check, a casing having an annular channel therein, an abutment and a wing piston dividing the channel into two working compartments, a spring actuated member serving as a shaft in said casing, the piston being operated by said spring actuated member, a cover for said casing, said cover co-operating with the casing to define an annular reservoir, and a check valve adapted to deliver liquid to a working compartment.

22. In a hydraulic check, a casing having an annular channel, an abutment and a wing piston dividing the channel into two working chambers, a spring actuated member serving as a shaft, said piston being secured to said member, a cover for said casing, said cover having a channel cut in a peripheral part thereof, said channel being closed by a part of the casing to form a reservoir, a check valve controlling a flow of liquid from the reservoir, and a vent valve for relieving pressure within the reservoir.

23. In a hydraulic check, a casing having a pair of working compartments, a rotatable member serving as a shaft being in said casing, a piston operated by said rotatable member, an annular wall serving as a closure for an end of the casing, a substantially arcuate member being carried by said wall, and means for adjusting the said arcuate member.

24. In a hydraulic check, a casing having a pair of working compartments, a rotatable member serving as a shaft being in said casing, and a piston operated by said rotatable member, said piston having a key integral therewith, said key extending into a recess in a wall of the rotatable member, and the key being smaller than the recess to permit a limited movement of the piston relative to the rotatable member.

25. In a hydraulic check, a casing having an annular chamber, a piston and an abutment in said annular chamber, a member serving as a shaft operating said piston, a spring being adapted to return the member to an initial position, an anchor for the spring, said anchor having engagement with a tension member, means for moving said spring seat relative to the tension member, and means for selectively locating the tension member to reverse the action of the spring.

26. In a hydraulic check, a casing having an annular chamber, said annular chamber having a bottom wall and a top wall, a piston and an abutment dividing the annular chamber into two compartments, the bottom wall comprising an annular passage joining the two compartments, and means for regulating a flow of fluid through the passage.

27. In a hydraulic check, a casing having an annular chamber, a piston and an abutment dividing the annular chamber into a pair of compartments, a cover for the casing having a reservoir, a tubular member serving as a shaft, a bearing for said tubular member in said cover, and an annular passage within said cover adjacent to the tubular member, said passage serving as a collecting chamber, and an opening between said annular passage and said reservoir.

28. In a hydraulic check, a casing having an annular chamber, said annular chamber having a top wall and a bottom wall, a piston and an abutment dividing the annular chamber into two

compartments, a tubular member serving as a shaft, said tubular member having a bearing in the bottom wall, an annular passage adjacent to said bearing, and an opening connecting the annular passage with an interior part of the tubular member.

29. In a hydraulic check, a substantially cylindrical casing having an annular chamber, a piston and an abutment dividing the annular chamber into a pair of compartments, a member in said casing serving as a shaft, the said piston having an axially extending passage, a substantially cylindrical valve in said passage, a thermostatic element engaging said valve, and means for selectively locating said thermostatic element in the passage.

30. In a hydraulic check, a casing, an arm actuated member serving as a shaft within the casing, said casing and said arm actuated member defining an annular channel, a member in said channel dividing the channel into a pair of working compartments, means holding said member relative to a wall of the channel, said holding means having clearance to permit a pressure of fluid to move said member into sealing contact with said wall, a passage through said member, a substantially cylindrical valve in said passage, and a temperature responsive element engaging said valve, said element extending substantially axially through said member.

31. In a hydraulic check, a casing, an arm actuated member serving as a shaft within the casing, said casing and said arm actuated member defining an annular channel, a member in said channel dividing the channel into two working compartments, means holding said member relative to a wall of the channel, and a passage through said member, a strip of metal being attached to a wall of the member at a substantial

distance from the passage, and the said strip being bent by a flow of fluid to open and close said passage.

32. In a hydraulic check, a casing, an arm actuated member serving as a shaft within the casing, said casing and said arm actuated member defining an annular channel, an abutment in said channel dividing the channel into two working compartments, and means holding said abutment relative to a wall of the casing, the member serving as a shaft having a part of its surface cut away to provide a passage between the working chambers when the said part of the surface thus cut away passes the abutment.

33. In a hydraulic check, a casing, a hollow arm actuated member serving as a shaft within the casing, said casing and said arm actuated member defining an annular channel, an abutment in the channel, the hollow arm actuated member containing working fluid, a poppet type vent valve in said arm actuated member, said vent valve comprising a head and a split stem, the head of said last named member engaging a seat in the arm actuated member, the split stem of the valve being spread to engage a surrounding spring, and the spring being tensioned to hold the said head of the valve on a seat.

34. In a hydraulic check, a casing, an arm actuated member serving as a shaft within the casing, said casing and said arm actuated member defining an annular channel, an abutment in the channel dividing the channel into two working compartments, a cover for the casing, a passage in the cover, the said passage connecting the working compartments, a substantially cylindrical valve in the passage, and an arm for rotating said valve, said arm being adaptable to be bent to a desired position.

COURTNEY N. MITCHELL.
